MACHINE FOR DISPENSING RODLIKE ARTICLES, SUCH AS SUGARCANE SETTS

Rutherford S. L. Hulett, Umhlanga, Natal, Union of South Africa

Application May 6, 1950, Serial No. 160,454
In the Union of South Africa May 10, 1949

4 Claims. (Cl. 222—10)

1

The invention relates to machines for dispensing individual rod-like articles from a mass of such articles and relates particularly to the planting of sugar cane setts.

As far as the applicant is aware, no successful, fully-mechanised planting machine for planting sugar cane setts has yet been achieved, and it is the object of the present invention to provide such a machine.

According to the invention, a machine for dispensing individual rod-like articles in succession from a mass of such articles consists in a hopper for the mass the width of which exceeds the length of the articles to be dispensed, a discharge passage from the hopper communicating with the hopper through an elongated throat long and wide enough to pass a single article at a time, a hinged element at the throat, a spring biasing the element to a position in which it obstructs the throat; a feed roller rotatable about a horizontal axis and having a number of radial projections the orbit of which intersects the path of articles gravitating down the sloping floor to the throat, the shape of the projections and their direction of rotation being such that one article at a time is engaged and propelled downwardly into the throat; an isolating roller above the throat rotatable about a horizontal axis in the direction opposite to that of the feed roller and having a series of circumferentially spaced radial projections the orbit of which intersects the path of articles that have passed the feed roller and are approaching the throat; and means to displace the hinged element and to propel each article in turn through the throat.

Further according to the invention, the ejecting means consists in several parallel flexible bands mounted for movement transverse to the length of the throat and the surfaces of which are adapted frictionally to engage articles in the throat and propel them through the throat.

The invention also includes a roller arranged in the path of the gravitating articles, the periphery of which is shaped to engage and align the articles to be parallel with the throat, the axis of the aligning roller being parallel with the axes of the feed and isolating rollers.

From the hopper, the articles gravitate towards the throat (e. g. down an inclined floor sloping towards the throat) and as they approach it they are engaged by an aligning means which corrects any deviation from parallelism with the throat. After having been thus aligned, the articles in turn pass to the feed roller which propels them towards and through the throat.

2

Only one article at a time is permitted to enter the throat. This is achieved by an isolating means which periodically retracts to allow a single article to enter the throat, and then holds back the following articles until the occupant of the throat has been ejected.

An embodiment of the invention is illustrated in the accompanying drawings in which:

Figure I is a part plan view;

Figure II is a front end elevation;

Figure III is a view from one side;

Figure IV is a view from the opposite side;

Figure V is a vertical section on the line V—V,

Figure I; and

Figure VI is a perspective view of the planting means.

The machine illustrated includes a frame 2, mounted on a pair of landwheels 3, keyed on to a common axle 4; and a drawbar 5 to hitch the machine to a tractor. The frame 2 carries a coulter 6 which, on forward movement of the machine, digs a furrow 7 (Figures I and V). The frame may also carry fertiliser-dispensing mechanism which, as it is impertinent to this application, is not illustrated.

An endless chain conveyor 8 is mounted on the frame 2, for movement around a spaced pair of sprockets 9 (see Figure V). Cane setts 10 to be planted are fed on to the conveyor 8, and drop therefrom into a hopper 11. Referring to Fig. I, the hopper contains a moveable plate 12, with an upwardly directed handle 13, and attached to the rear of the plate is a guide rod 14, slidably mounted in a bearing 15.

When the hopper has received a charge of setts, the plate 12 is moved to sweep out the hopper and propel the setts from the hopper on to an inclined platform 16 (see Figure V) which is flanked by parallel side walls 16b carried by the frame 2.

On being launched on to the platform, the setts 10 sort themselves out and roll downwardly more or less in single file, as shown in Figure V. During their descent, they come up against an aligning roller 17 which is formed with a series of parallel recesses 18 spaced circumferentially around its periphery. Each sett in turn, as it makes contact with the roller 17 is engaged by one of the recesses 18 and is aligned by the shoulder 18a of the recess to lie in the direction of the furrow 7, that is to say in the direction of forward movement of the machine.

Rotation of the roller 17, combined with gravity, moves the aligned set forward, over the roller and on to a feed roller 19 of quatrefoil

cross-section, which propels each sett in turn into a pocket 20 defined by the roller 19, the terminal part 16a of the inclined platform, a spring loaded flap 21, and a pair of chains 22.

Each sett in turn enters the pocket and is there isolated from the sett or setts following it down the slope by a selector mechanism consisting of a roller 23 which has a series of spaced parallel radial projections which, in the embodiment illustrated, are curved leaf spring fingers 24 secured to the surface of the roller 23. The fingers are spaced apart both circumferentially and in the axial direction to leave spaces for the chains 22.

The rotation of the roller 23 is opposite to that of the rollers 17 and 19 so that the fingers 24 sweep out a path which is such that the following sett comes within its orbit and is repelled away from the pocket 20, or at least retarded from entering it, so as to prevent the following setts from jamming at the entrance to the pocket.

The sett in the pocket is frictionally engaged by the chains (which are moving downwardly) and is propelled through the throat 25 resulting from depression of the flap 21 against the resistance of the torsion spring 26 which biases the flap to close the throat but which yields to allow the flap to be displaced to pass the sett.

The flap is curled around a rod 27 journaled in the side walls 16b. The spring is anchored on a collar 28, which is screwed on to the rod 27 outside one of the side walls 16b, and on a stop 29 on the wall. The tension of the spring may be adjusted by altering the angularity of the collar 28 relatively to the rod 27.

The upward movement of the flap 21 towards the chains 22 is limited by an arm 30 projecting radially from the rod, and making contact with a stop 31 on the side wall 16b.

The effective width of the pocket 20 may be adjusted to suit setts of different diameters, by moving the selector roller 23 towards or away from the feed roller 19, and locking it in the adjusted position. For this purpose, the pin 32 on which the roller is mounted is journaled in blocks 33 which are slidably arranged in slotted guides 34. The blocks are held in position by means of a set screw 35 engaged with one end wall of each block, and which presses the block away from the feed roller 19 against the resistance of a compression spring 36.

The construction described has the advantage also that if an oversize sett approaches the pocket, the selector roller 23 is able to yield resiliently to allow the sett to pass into and be propelled from the pocket.

It is pointed out that the chains 22 have sufficient slack and flexibility to allow them to be deflected in the neighbourhood of the pocket, by the pressure of the sett on the chains, as is well illustrated in Figure V.

The chains are simultaneously pressed against the periphery of the selector roller 23 in the spaces between the fingers 24 so that the chains are curved around an arc of the sett. This acts to increase the frictional engagement with the sett which propels the latter through the throat 25.

The sett enters the throat 25 parallel with the various rollers 17, 19 and 23. As it passes through the throat, one end of it, that numbered 10a in Figures II and VI, displaces a leaf spring 37 arranged in its path, and is momentarily retarded, relatively to the other end 10b, so that the sett emerges from the throat 25 in an inclined position. The end 10b strikes the floor of the furrow

7 as shown in Figure VI while the end 10a is still up in the air or even still engaged by the spring 37. The sett then pivots about the end 10b until it comes to rest in the furrow, aligned with the length of the latter, as shown at 10c in Figure VI.

The next succeeding sett then enters the pocket 20 at a moment when the fingers 24 are so positioned as to allow the sett to slip past the roller 23 without being retarded or repelled by the fingers which, however, obstruct the following sett, as above explained.

In case setts build up above the pocket, a fence is provided to stop setts from fouling the chains. This fence consists of a series of parallel pickets 38 more or less in the plane of the chains. The lower ends of the pickets terminate just above the orbits of the fingers 24, and the leaf spring 37 is mounted on one of the pickets 38.

The driving arrangements for the various moving parts described are particularly clearly illustrated in Figure I, but can also be seen in the other figures.

The drive is taken from the axle 4 by a sprocket 39 through a chain 40 to a sprocket 41 on a countershaft 42.

The drive is transmitted to a shaft 43 at right angles to the countershaft through bevel gears 44. The shaft 43 carries the aligning roller and a gear 45 which meshes with a gear 46 on a stub shaft 47 journaled in one side wall 16b. The shaft 47 also carries a sprocket 48 which through a chain 49 drives a sprocket 50 on a shaft 51. The sprockets 52 which drive the chains 22 are mounted on the shaft 51. The upper sprockets 53 are idlers on a shaft 54 journaled in the side walls 16b.

The shaft 51 extends rearwardly and towards its end it carries a sprocket 55 which, through a chain 56, drives the sprocket on the same shaft 57 on which one of the chain conveyor sprockets 9 is mounted.

The shaft 43 also carries a sprocket 58 which, through a chain 59, drives the shaft 60 on which the roller 19 is mounted.

The drive for the selector roller 23 is taken from the shaft 60 through the chain 61, which chain is tensioned by a jockey roller 62, to enable the selector roller 23 to be adjusted, as above described.

The driving arrangements described include two clutches, one 63 between the rear axle 4 and the countershaft 42; and the other 64 between the shaft 51 and the conveyor 8. Thus, the planting mechanism may be declutched as a whole, or merely the drive to the conveyor to enable the plate 12 to sweep out the hopper 11 from time to time.

The ratio of the drive between the axle 4 and the various moving parts of the machine may be made variable, to enable the spacing of the planted setts to be varied.

I claim:

1. A machine for dispensing individual rod-like articles from a mass of such articles, including a hopper for the mass of articles, the width of which exceeds the length of the individual articles of the mass, and the floor of which slopes downwardly; a discharge passage at the lowest point of the floor that constitutes an elongated throat long and wide enough to pass a single article at a time, a hinged element at the throat, a spring biasing the element to a position in which it obstructs the throat; a feed roller rotatable about a horizontal axis and having a number of radial projections the orbit of which

intersects the path of articles gravitating down the sloping floor to the throat, the shape of the projections and their direction of rotation being such that one article at a time is engaged and propelled downwardly into the throat; an isolating roller above the throat rotatable about a horizontal axis in the direction opposite to that of the feed roller and having a series of circumferentially spaced radial projections the orbit of which intersects the path of articles that have 10 passed the feed roller and are approaching the throat; and article expelling means at said throat spaced from said hinged element a distance less than the transverse dimension of the article to expell the article and displace the element.

2. The machine of claim 1 in which the expelling means consists in several parallel flexible bands mounted for movement transverse to the length of the throat and the surfaces of which are adapted frictionally to engage articles in the throat and propel them through the 20 throat.

3. The machine claimed in claim 2 in which each flexible band is an endless chain the links of which engage the article to be propelled. 25

4. The machine claimed in claim 1 including a roller arranged in the path of the gravitating articles and the periphery of which is shaped to engage and align the articles to be parallel 5 with the throat, the axis of the aligning roller being parallel with the axes of the feed and isolating rollers.
